UNITED STATES PATENT OFFICE.

EDWIN W. WOOD, OF LOCKRIDGE, OKLAHOMA.

FLY SWATTER.

Application filed March 4, 1926. Serial No. 92,141.

My invention relates to improvements in fly swatters.

The object of the invention is to provide a swatter of the character and combination of parts as described, whereby to enhance the efficiency, facilitate the use and prolong the life of the use of such devices; one which will be cheap, durable, practical and ready for instant use at all times.

10 Other objects and novel features of the invention will more fully appear from the specifications, claims, and one sheet drawing, of which:—

15 Figure 1 is a plan view of the device showing the handle with the screen wire and binding means mounted on the frame. Figure 2 is a plan view of the device showing the frame without the screen wire and binding means.

20 Like characters of reference designate like parts in all the figures.

The device is composed of a wire handle the two strands of which are held together for said length, 2, 2^a, by two ferrule members 3, 4; above the upper ferrule member 4 the two strands 2, 2^a, diverge oppositely, diagonally and upwardly and outwardly 5, 6; and thereafter are bent inwardly, horizontally 7, 8, to a common meeting point in the center of the handle 9, 10, and forming triangular bracing arms. The frame of the swatter is preferably rectangular in form, though it may be of other forms, if desired, and is made of a single piece of wire. One of its ends is anchored by convolutions 11 around the diagonally, upwardly extending arm 5, a strand of said wire 12 extends upwardly from said convolutions 11 to inwardly extending arm 10 where second convolutions 13 near the angle bent portion 7 encircle said arm and from there extends perpendicularly at 14, horizontally at 15, downwardly perpendicularly at 16, to a third set of convolutions 17 encircling arm 9 near the angle 8 from the end of which convolution extends a strand 18 to a fourth convolution 19 of said wire surrounding said upwardly extending arm 6. A screen mesh 20 or other meshed material covers said frame and is held in place by felt, leather, or suitable binding cloth 21, preferably stitched thereon.

It is known to those familiar with the art to which my invention pertains that where 55 no spring action independent of that furnished by the handle member and the wire

screen, is not provided in the proximity of the joining of the handle member and the frame of the swatter that the constant use of the swatter causes the breaking of the frame, and the breaking and tearing of the binding cloth, and screen wire surrounding the frame rendering such swatter unusable. It is also found by those familiar with the art, the use of the spring without a sufficiently firm anchoring thereof simply accentuates the flexing movements of the swatter forwardly and backwardly making said flexing movement an almost constant one thereby wearing out the mesh screen and the binding cloth to practically the same extent as without any spring member thereon; it is also known to those familiar with the art that a single straight strand of each end of the coil spring extended to and seated in a ferrule member with the almost constant flexing as above described constantly prying on said ferrule member will soon result in the same being torn or split, thereby shortening the life of the swatter and rendering same unusable on finished wood, furniture and the like, on account of marring and scratching the same.

The double triangular shape of the upper part of the handle in our device together with the four coils or convolutions surrounding four different parts thereof give to our device sufficient spring flexing ability to permit of easy and accurate use and yet to at once cause the swatter to return to its normal position for further use. The firmness of the upper portion of the handle and of the anchoring of the spring wire frame thereon as above described makes it practically impossible to wear out the swatter. The fastening of the two strands of wire for a portion of the length of the handle member, side by side with two ferrule members a distance from each other add stability and rigidity to that portion of the handle member and to the triangular member thereabove and assists in preventing movement of the upper portion of the handle member enclosed by the screen mesh and the binding cloth.

From the description and the accompanying one page drawing, and the specifications, the advantages of construction, application and manufacture will be apparent to those skilled in the art to which my invention pertains. I have entered into a detailed description of the construction and relative ar-

angement of the parts embraced in the present and preferred embodiment of my invention in order to impart a full, clear and exact understanding of the said embodiment. I
5 do not desire, however, to be understood as confining myself to the specific construction and relative arrangement of parts inasmuch as in the future practice of the invention various changes and modifications may be
10 made as fall within the scope of my invention as defined in my appended claims, without departing from the principle of the invention.

Having thus described the invention, what
15 is claimed and desired to be secured by Letters Patent, is:—

1. A swatting device of the character described, comprising a handle member, its upper portion first bifurcated then bent backwardly upon itself, its ends axially meeting
20 at a common center; a single spring wire frame member forming a rectangle and forming coiled spring convolutions, the convolutions of the wire in each adapted to
25 fit closely together and to encircle respectively the axially bent ends of said upper handle and adapted to be anchored respectively on the bifurcated arms thereof, said coil spring convolutions adapted to give
30 spring resilience to said fly swatter and to adaptably hold the same in working position; a meshed wire screen adapted to fit
1 and around said frame; a suitable bind-

ing adapted to be fastened to and around said frame and to and around said edges 35 of said meshed screen wire by suitable holding means.

2. A swatting device of the character described, comprising a spring wire handle member with a partially rigid upper portion, and two oppositely outwardly and upwardly extending portions thereabove and an inwardly bent horizontal portion on the end of each, axially aligned and ending at a common center; a single spring wire frame 45 member describing a rectangle, its ends anchored by coiled spring convolutions encircling said respective oppositely outwardly and upwardly extending portions intermediate their respective ends; two other coiled 50 spring convolutions encircling respectively the inwardly bent axially aligned portions, said coiled spring convolutions adapted to give spring resilience to said fly swatter and to adaptably hold the same in working position; a short portion of said wire respectively connecting the said first two described coiled spring convolutions and said second two described coiled spring convolutions; a mesh screen wire adapted to fit foldingly 55 over said frame and to be securely fastened thereto; a suitable cloth binding adapted to be fastened to and around said frame and said edges of said mesh screen wire.

EDWIN W. WOOD.
